(57) **CLAIM**

The ornamental design for a lantern body as shown and described.

DESCRIPTION

FIG. 1 is a front, right and top perspective view of a lantern body showing our new design;

FIG. 2 is a rear, right and bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, right and top perspective view of the lantern body in accordance with our new design illustrating a state in which an environmental structure (a battery) is attached to the lantern body.

The broken lines in the drawings illustrate the environmental structures or portions of the lantern body which form no part of the claimed design.

1 Claim, 9 Drawing Sheets
